UNITED STATES PATENT OFFICE.

AUGUST HEMME, OF DUBLIN, ONTARIO, CANADA.

TRAP.

1,233,573.

Specification of Letters Patent. Patented July 17, 1917.

Application filed September 20, 1916. Serial No. 121,263.

To all whom it may concern:

Be it known that I, AUGUST HEMME, of the village of Dublin, in the county of Perth, in the Province of Ontario, Canada, have 5 invented certain new and useful Improvements in Traps, of which the following is the specification.

My invention relates to improvements in animal traps and the object of the invention 10 is to devise a simple, effective and cheap form of trap for catching animals such as rats and mice and it consists essentially of a casing having an open top, a removable cover for such open top, an opening in the 15 cover, a wall extending from the cover around the edge of the opening, a spring held flap pivoted beneath the cover and extending beneath the aforesaid opening, means for regulating the tension of the 20 spring, and bait supporting means extending from the inner face of the wall surrounding the cover opening as hereinafter more particularly explained by the following specification.

25 Figure 1, is a perspective view of my device.

Fig. 2, is a longitudinal section through Fig. 1.

30 Fig. 3, is an enlarged perspective detail of the pivoted flap.

In the drawings like figures of reference indicate corresponding parts in each figure.

1 is a container or casing having an open top and a vertical slot 2 in the front wall 35 thereof (see Fig. 2). 3 is a cover for the open top of the casing 1 having a surrounding depending edge rim 4 fitting around the upper edge of the open top of the casing 1 when the cover 3 is in position. 5 is a longitudinal slot formed in the cover 3. 6 is a rectangular opening (see dotted lines Fig. 1) also formed in the cover 3 at the opposite end to that in which the slot 5 is located. 7 is a wall extending upwardly from the 45 cover 3 and extending around the edge of the opening 6. The inner portion 8 of the surrounding wall 7 is preferably of less height than the opposite portion 9. The upper edges of the end portions 10 and 11 are inclined upwardly from the top of the portion 8 to the top of the portion 9.

50 12 is a bait hook secured to the inner face of the wall portion 9 and on which suitable bait 13 is held. 14 is a notch formed in each longitudinal side wall of the container 1. 15

is a rod extending through the notches 14 passing at its ends into the depending rim portion 4 of the cover 3. 16 is a flap which is preferably formed as shown particularly in Fig. 3 with a longitudinal slot 17, an inwardly rolled portion 18 which wraps around the rod 15, and a tongue 19 which extends centrally from the end of the rolled portion 18. The tongue 19 as will be clearly seen in this figure passes through the slot 17 as the rolled portion 18 is formed and the tongue assumes a position extending horizontally at a slightly higher level than the body of the flap 16. Thus when the flap 16 is in position within the container as shown 60 particularly in Fig. 2, the body of the flap extends in its normal position against the under face of the cover portion 3 and beneath the rectangular opening 6 so as to form a closure for the same. The tongue 65 portion 19 when the flap is in this position fits into the slot 5 formed in the cover so as to form a closure for the same when the flap is in the normal position. 20 is an L-shaped eye bolt the horizontal portion of the bolt 70 being threaded and extending through the slot 2. The horizontal portion of the eye bolt 20 is also provided with an enlargement 21 which is wider than the slot 2 and bears against the inner face of the 75 wall of the container. 22 is a butter-fly nut screwed onto the threaded portion of the eye bolt against the outer wall of the casing. 23 is a tension spring connected at one end to the eye of the eye bolt 20 80 and at the opposite end to an eye 24 carried by the outer end of the tongue 19. 25 and 26 are pins extending laterally from the rim 4 of the container cover 3. 27 are hooks pivotally connected to the side walls 85 of the container and designed to hook over the laterally extending pins 25 and 26 to hold the cover in place.

When in use the trap is placed on the ground and a stick or other suitable means 100 is laid against the container in a slanting position so as to form a run-way for the animal onto the top of the container. The animal attracted by the bait climbs over the low end wall portion 8 of the 105 surrounding wall 7 and jumps onto the flap 16 which forms a yieldable closure for the opening 6. The opposite wall 9 is preferably higher so that the animal cannot reach over to the bait from that side 110

of the opening. As soon as the animal jumps on to the flap 16 the spring yields allowing the flap to swing downwardly throwing the animal into the casing 1. 5 As soon as the flap is relieved of the weight of the animal it immediately flies up into the normal position so as to again close the opening 6. It may be found necessary from time to time to adjust the tension of 10 the spring 23 either owing to the spring becoming weak or it being necessary to strengthen or weaken the spring according to the weight of the animal it is desired to catch. The tension of the spring may be 15 adjusted by simply loosening the nut 22 and adjusting the bolt 20 vertically in the slot 2. As soon as this is done the nut is again tightened.

From this description it will be seen that 20 I have devised a very simple form of trap which may be adapted for catching small animals and which will be efficient and not

harm the animal and therefore, will be less cruel in its action.

What I claim as my invention is:

An animal trap comprising a container having a suitable cover having an opening therein, a wall extending upwardly from the container cover and surrounding such opening, bait supporting means carried by the wall, a flap pivotally supported within the container and designed at its free end to close the opening in the container cover when in its normal position, a tongue extending rearwardly from the flap from the opposite side to its point of swing, a tension spring secured to the end of the tongue, and adjustable means for securing the opposite end of the spring to the wall of the container, as and for the purpose specified. 35 40

AUGUST HEMME.
